No. 651,290.

Patented June 5, 1900.

T. BLACKERBY.

HEN'S NEST.

(Application filed Sept. 8, 1899.)

(No Model.)

A diagram of a stepped rectangular base. The base is divided into three horizontal sections by two horizontal lines. The top section is the widest, followed by a narrow middle section, and a wide bottom section. A central rectangular cutout is located in the middle section, with its top edge aligned with the top horizontal line and its bottom edge aligned with the bottom horizontal line. The left and right edges of the base are straight vertical lines.

UNITED STATES PATENT OFFICE.

THOMAS BLACKERBY, OF HERRICK, ILLINOIS.

HEN'S NEST.

SPECIFICATION forming part of Letters Patent No. 651,290, dated June 5, 1900.

Application filed September 8, 1899. Serial No. 729,873. (No model.)

To all whom it may concern:

Be it known that I, THOMAS BLACKERBY, a citizen of the United States, residing at Herrick, in the county of Shelby and State of Illinois, have invented a new and useful Hen's Nest, of which the following is a specification.

The invention relates to improvements in hens' nests.

One object of the present invention is to improve the construction of hens' nests and to provide a simple, inexpensive, and efficient one having an automatically-closing door adapted to close and open when a fowl enters and leaves the nest.

15 A further object of the invention is to provide a device of this character adapted to be readily cleaned and capable of being arranged to form a shelter for a hen and her brood.

The invention consists in the construction 20 and novel combination and arrangement of parts hereinafter fully described, illustrated in the accompanying drawings, and pointed out in the claims hereto appended.

In the drawings, Figure 1 is a longitudinal 25 sectional view of a hen's nest constructed in accordance with this invention. Fig. 2 is a similar view, the nest being inverted to form a shelter for a hen and her brood. Fig. 3 is a detail perspective view of the pivoted door.

30 Fig. 4 is an enlarged detail sectional view illustrating the construction of the upper end of the legs.

Like numerals of reference designate corresponding parts in all the figures of the drawings.

35 1 designates a frame or casing composed of upper and lower portions 2 and 3 and adapted to be inverted for a purpose hereinafter described. The lower section is composed of 40 sides 4, a back 5, and a cross-piece 5^a, and it is supported by legs 6 and 7, which project above the upper edges of the sides of the lower portion to support the upper section 2 and prevent the same from slipping off the 45 upper edges of the lower section. The cross-piece 5^a forms a partial platform and is interposed between a nest-box 8 and a pivoted door 9, which is automatically swung upward and closed by the weight of a fowl when the 50 same is on the nest-box. The nest-box, which is arranged in the space between the platform

and the back 5, is provided at its rear edge with eyes 10 for the reception of a removable pintle-rod 11. The nest-box is provided with forwardly-extending arms 12, arranged beneath the platform and connected with the inner or lower end of the upwardly-swinging door, which is pivoted at opposite sides of the lower section of the frame or casing at 13. The arms preferably consist of extensions of 60 the sides of the nest-box, and they are provided with flexible connections 14, such as short cords, which are adapted to be secured to fastening devices 15 and 16, such as pins or screws. The pivot of the upwardly-swinging 65 door is located at a point near the inner or lower ends thereof, and the fastening devices 15 and 16 are located at different points from the pivot, and by arranging the devices at different distances the leverage may be varied to suit the weight of a fowl. The door 70 is supported in a horizontal position by a transverse bar 17, and when open it combines with the platform to form a walk to the nest-box. As soon as a fowl steps from the platform to the nest-box the door closes slowly, and as soon as it leaves the nest-box the door 75 opens gently. When a fowl is on the nest, the door remains closed and it cannot be disturbed.

80 The upper section 2, which is composed of sides, a top, and a back, is open at the front, and it is arranged within the projecting upper portions of the legs, which are beveled at their inner faces and which are located at 85 the outer faces of the sides of the upper section. In order to prevent the upper section from moving longitudinally of the lower section, it is provided at its back with depending projections 18, spaced apart to receive 90 the back of the lower section. By this construction the upper section is detachably interlocked with the lower section and the parts may be readily separated to afford access to the interior of the nest for the purpose of 95 cleaning the same.

When the device is inverted, as illustrated in Fig. 2 of the accompanying drawings, it is adapted to form a shelter for a hen and her brood, and the door may be supported at an 100 inclination by a pivoted button 19, recessed at 20, to form a supporting-shoulder and

adapted to engage a recessed portion 21 of the pivoted door. The door may be supported upon the shoulder formed by the recess 20 or by the outer end of the button and may 5 be set at different inclinations to suit the size of the chickens.

It will be seen that the nest is simple and comparatively inexpensive in construction, that it is positive, reliable, and automatic in 10 operation, and that it is capable of adjustment to vary the leverage of the pivoted door. It will also be apparent that it affords a complete protection for a fowl and that it may be readily arranged to provide a shelter for 15 a hen and a brood.

Changes in the form, proportion, size, and the minor details of construction within the scope of the appended claims may be resorted to without departing from the spirit or sacrificing any of the advantages of this invention.

What is claimed is—

1. A device of the class described comprising a casing adapted to be inverted and composed of upper and lower sections detachably interlocked, a pivoted door mounted on the lower section of the casing and arranged to swing upward, a nest-box hinged to the casing and connected with the door, and a 25 vice mounted on the upper section of the casing and arranged to support the door at an inclination to hold the same partially open when 30

the casing is inverted, substantially as described.

2. A device of the class described comprising 35 a casing adapted to be inverted, a pivoted door mounted on the lower portion of the casing and adapted to swing upward, a nest-box hinged to the casing and connected with the door, and a device mounted on the upper portion of the casing and arranged to support the door at an inclination to hold the same partially open when the said casing is inverted, substantially as described.

3. A device of the class described comprising 40 a casing composed of upper and lower detachably interlocked sections and adapted to be inverted, a nest-box hinged to the lower section of the casing, an upwardly-swinging door mounted on the lower section of the casing and connected to the nest-box, and a pivoted button mounted on the upper section of the casing and provided with a shoulder and adapted to support the door at different inclinations when the casing is inverted, substantially as described.

In testimony that I claim the foregoing as my own I have hereto affixed my signature in the presence of two witnesses.

THOMAS BLACKERBY.
